UNITED STATES PATENT OFFICE

117,297

DESIGN FOR A DIRECTION SIGNAL

Henry W. Sobke, Calexico, Calif.

Application May 1, 1939, Serial No. 84,704

Term of patent 7 years

To all whom it may concern:

Be it known that I, Henry W. Sobke, a citizen of the United States, residing at Calexico, in the county of Imperial and State of California, have invented a new, original, and ornamental Design for Direction Signals, of which the following is a specification, reference being had to the accompanying drawing, forming part thereof.

Figure 1 is a side view of a direction signal, showing my new design.

Figure 2 is an end view of the same.

The opposite side of the direction signal is substantially the same as the side disclosed in Figure 1.

I claim:

The ornamental design for a direction signal, as shown and described.

HENRY W. SOBKE.
